UNITED STATES PATENT OFFICE

THOMAS HERBERT COGGINS AND ALBERT FARRINGTON, OF ASTON, BIRMINGHAM,
ENGLANDPROPELLER OF MOTOR-DRIVEN CANAL AND OTHER BOATS, RIVER BARGES, AND
THE LIKE

Application filed April 9, 1929, Serial No. 353,855, and in Great Britain April 10, 1928.

Motor-driven propeller units are known for detachable application to boats, barges and the like. In canals and other shallow water-ways great difficulty is experienced in the use of such motor driven propeller units in consequence of obstructions in the water-ways and of the varying depths encountered fouling the propeller.

The invention provides a motor-driven propeller unit for the purpose, particularly applicable to canal boats, in which the propeller is arranged to be automatically lifted, or moved, so as to clear itself of obstruction in the water-way, that is to say, given a normal dip of propeller if any obstruction in the water way is met which would be likely to damage the propeller and its operative parts the invention will cause said propeller to be automatically lifted or moved to clear itself of the obstruction, using the obstruction as the means for bringing into operation the lifting mechanism. In this way the propeller and its parts will be safe against damage.

A desirable embodiment of the invention arranges the propeller in relation to its mounting to be protected by a bump shield which will contact the obstruction and move upwardly lifting the propeller and its parts with it, to return to normal position after the obstruction has been passed. The fall or return of the propeller is by its own weight checked by resilient resistance which may be so arranged that normally the movable propeller and its parts will lift fairly easily and yet always maintain its requisite dip under normal conditions of drive. The lifting and lowering is without any disconnection of the drive of the propeller, and the movable parts operative in the lifting and fall are substantially above water-line.

Combined with the aforesaid features is an arrangement whereby the normal dip of the propeller on its vertically stationary but detachable mounting is capable of being hand adjusted relatively to the depth of the water and the load of the boat or barge.

One arrangement according to the invention provides a vertical tubular pillar which by detachable bracket mounting can drop onto and lift off supports on the end of the

boat or barge. This tubular pillar except for steering is stationary and has working within it a telescopic sleeve whose lower end provides a bearing outside the pillar for a short propeller shaft which is at right-angles to the pillar and sleeve. A telescopic drive passes through the pillar and sleeve to drive the propeller shaft from a drive shaft above the pillar. Slidably fitted over the pillar is a rigidly built frame from which are slidably suspended vertical carrier rods connecting at their lower ends with bearings of the propeller shaft and fitted at their upper ends with resilient springs which co-operate between the rods and frame. The frame and sleeve and the propeller shaft adjust vertically upon and within the pillar by screw action, so that the normal position of the propeller shaft can be lifted or lowered, but between the frame and the propeller shaft there is a vertical resilient engagement through the carrier rods and springs so that quite independent of the position of the frame the propeller shaft can automatically lift and lower.

The propeller is protected by a guard which contacts the obstruction so that the propeller blades are never fouled but only the guard protecting same.

The accompanying drawings show a desirable embodiment of the invention.

Fig. 1 is a sectional elevation of the complete unit, part of the drive shaft and the steering bar being broken away.

Fig. 2 is an enlarged side elevation of the lower portion of Fig. 1.

Fig. 3 is a rear end view of Fig. 2.

The unit is constructed about a vertical tubular pillar *a* which is rigidly built with upper and lower bracket mountings *c* and *d* adapted by peg and socket engagement to drop onto and lift off corresponding supports fixed to the end of the canal boat it being desirable in the use of the invention that the unit shall be conveniently and quickly transferred to different boats for use while other boats are being loaded and unloaded. This tubular pillar *a* is vertically stationary but it swings in the horizontal plane for steering purposes on its bracket mountings to the boat end, a steering bar

being represented at *e* for hand operation. Arranged within this tubular pillar *a* is a telescoping sleeve *f* whose lower end projects from the pillar and provides at *f*² a bearing for a short propeller shaft *g* at right-angles to the pillar and sleeve. The sleeve is supported by the tubular pillar and turns only therewith but can slide up and down therein independently as will be hereinafter further explained.

10 A telescopic drive passes through the pillar and sleeve to drive the propeller shaft *g* from a driveshaft *h* arranged above the pillar. The shaft *h* drives a bevel gear *h*² which in turn drives a telescoping shaft *i* passing downwardly through the pillar and sleeve and the rotation of this shaft is communicated to the propeller shaft *g* by the bevel gears *j*. The reason for the shaft *i* being telescopic is because the sleeve *f* carrying the propeller shaft *g* telescopes within the tubular pillar *a* and it will be obvious that the divided telescoping shaft *i* will carry out the purpose.

25 Slidably fitted to the pillar *a* is a rigidly built frame *l* turnable with the pillar when the latter is moved from the bar *e* for steering. Slidably suspended from this frame *l* are four vertical carrier rods *m* connecting at their lower ends with two plate-like guards *n* one each side the propeller which guards rigidly connect low down at *o* with the bearings of the propeller shaft *g*, and serve as a rudder.

30 35 The rods *m* hang from the frame *l* by compression springs *q* and by an extension spring *r* and as the sleeve *f* is rigidly connected with the bearings of the propeller shaft *g* these springs suspend the sleeve, bearings, propeller shaft, propeller and guards from the frame *l* which by the screw *s* mounted in the upper part of the pillar to be revolved and the screw box *s*² carried by the frame *l* is adjustably supported from the pillar *a* so that the normal position of the propeller shaft can be lifted or lowered for varying the dip of the propeller to depths of water-ways, such being hand controlled by operation of the winding handle *s*³.

40 45 It will be therefore clear that the normal dip of the propeller is adjusted by the difference of the position of the frame *l* upon the pillar *a* and that quite independently of the position of the frame the propeller shaft can lift and lower on encountering any obstruction in the water-way, the sleeve *f*, bearings for the propeller shaft, the latter, the propeller and its plate-like guards being resiliently suspended by the rods *m* and springs *q* and *r* from the frame *l*.

50 55 The lower ends *n*² of the plate-like guards are fashioned to encounter the obstruction so that the propeller and its working parts are always safe against damage.

The springs *q* and *r* are calculated in strength to almost balance the weight of the parts arranged to automatically lift when the guards are encountering any obstruction so that very little effort is needed to cause 70 a commencement of the automatic lifting action.

Once the motor driven propeller unit is set in position and adjusted to the required 75 depth the propeller shaft will remain in such adjusted position until an obstruction is met by the guards which will contact and ride over the obstruction lifting the propeller clear and allowing it to fall again by its own weight after the obstruction has 80 been passed without in any way stopping the drive of the propeller or interfering with any of its working parts, and it may be convenient to arrange some sort of light 85 resilient devices to check the too quick fall of the lifted parts after clearing themselves of the obstruction.

Having now described our invention, what we claim and desire to secure by Letters Patent is—

90 1. A motor-driven propeller unit for boats, barges and the like, combining a pillar attachable to the end of a boat or barge, a frame mounted upon said pillar, a sleeve vertically slidable within the pillar and resiliently suspended from the frame, a propeller shaft mounted upon the lower end of the sleeve and fitted with a propeller, a guard fixed to the sleeve and mounting of the propeller shaft, a vertical shaft through the sleeve to drive the propeller shaft, and means for driving the vertical shaft, substantially as described. 95

100 2. A motor-driven propeller unit for boats, barges and the like combining a pillar attachable to the end of a boat or barge, a frame mounted upon said pillar, means for hand-adjusting the position of the frame upon the pillar and securing it, a sleeve vertically slidable within the pillar and resiliently suspended from the frame, a propeller shaft mounted upon the lower end of the sleeve and fitted with a propeller, a guard fixed to the sleeve and mounting of the propeller shaft, an extensible vertical shaft through the sleeve to drive the propeller shaft and means for driving the vertical shaft, substantially as described. 110

115 3. A motor-driven propeller unit for boats, barges and the like combining a pillar attachable to the end of a boat or barge, a frame mounted upon said pillar, a sleeve vertically slidable within the pillar, a propeller shaft mounted upon the lower end of the sleeve and fitted with a propeller, a guard fixed to the mounting of the propeller shaft and resiliently suspended from the frame, a vertical shaft through the sleeve to drive the propeller shaft, and means for driving said vertical shaft, substantially as described. 120

125 4. A motor-driven propeller unit for boats, 130

- 5 barges and the like, combining a pillar attachable to the end of a boat or barge, a frame adjustably mounted upon said pillar, a sleeve vertically slideable within the pillar, a
5 propeller shaft mounted upon the lower end of the sleeve and fitted with a propeller, a guard comprising two guard plates fixed to the mounting of the propeller shaft and resiliently suspended by springs from the
10 frame, a vertical shaft through the sleeve to drive the propeller shaft, means for driving said vertical shaft, and means for swinging the pillar upon its mounting to the boat or barge, substantially as described.
- 15 5. A motor-driven propeller unit for boats, barges and the like combining a pillar attachable to the end of a boat or barge, a frame rigidly mounted upon said pillar, a sleeve vertically slideable up and down within the
20 pillar by a straight-line motion, a propeller shaft mounted upon the lower end of the sleeve and fitted with a propeller, a guard fixed to the sleeve and mounting of the propeller shaft and suspended from the frame to support said sleeve and propeller from said
25 frame, a telescopic vertical shaft through the sleeve to drive the propeller shaft, and means for driving said telescopic shaft, substantially as described.

30 In testimony whereof we have affixed our signatures.

THOMAS HERBERT COGGINS.
ALBERT FARRINGTON.
